UNITED STATES PATENT OFFICE.

ERNEST OSCAR BUTT, OF NEW YORK, N. Y.

WATER-COOLER.

No. 819,850.

Specification of Letters Patent.

Patented May 8, 1906.

Application filed February 23, 1904. Serial No. 194,725.

To all whom it may concern:

Be it known that I, ERNEST OSCAR BUTT, a citizen of the United States, residing at New York, in the county of New York and State of New York, have invented certain new and useful Improvements in Water-Coolers, of which the following is a specification, such as will enable those skilled in the art to which it appertains to make and use the same.

10 This invention relates to water-cooling devices for use in offices, dwellings, and other places where devices of this class are required; and the object of the invention is to provide an improved device of this class which is designed for use in connection with a bottle or other water-receptacle having a neck from which the water continually flows into the cooler, the construction and arrangement being such that the flow of water from the bottle or other receptacle will be automatically cut off when the water in the cooler rises to a predetermined height; and with this and other objects in view the invention consists in a device of the class specified constructed 20 in a device of the class specified constructed as hereinafter described and claimed.

25 The invention is fully disclosed in the following specification, of which the accompanying drawings form a part, in which the separate parts of my improvement are designated by suitable reference characters in each of the 30 views, and in which—

Figure 1 is a sectional side view showing my improved water-cooler; Fig. 2, a front view thereof with part of the cover removed, 35 and Fig. 3 a section on the line 3-3 of Fig. 1 with the bottle or water-receptacle removed.

In the practice of my invention I provide a tank *a*, which is preferably circular in form and provided with double side walls and a 40 double bottom, between which are spaces *a*² and *a*³, which are filled or packed with any suitable non-heat-conducting material. The bottom of the tank *a* is provided with a depending annular flange or rim *a*⁴, which sits in and is supported by a suitable base-support *b*, having a flange or rim *b*², within which the flange or rim *a*⁴ fits, and the support *b* is dish-shaped in form in cross-section, so as to 45 form a drip-receptacle *c*. The support *b* containing the drip-receptacle *c* is mounted on a tubular upright standard *d*, having legs *d*², and in practice a bucket or other drip-receiver *d*³ is placed under the tubular upright standard *d*, and the support *b* is provided at 50 one side with an extension *b*³, over which is arranged a faucet *e*, which communicates

with the interior of the tank *a*, and the extension *b*³ of the support *b* forms a drip-receiver which is in communication with the drip-receptacle *c* and also preferably provided with 60 a screen *c*².

Within the tank *a* is placed an ice-receiver *f*, which is preferably circular in form and around which is an annular water-chamber *g*, and the ice-receiver *f* is provided at one side 65 with vertically-arranged radial walls *f*², forming a vertically-arranged radial passage *f*³, which communicates with a vertically-arranged supplemental water-chamber *f*⁴, which in the form of construction shown is 70 circular in cross-section and formed by the walls *f*², which also form the radial passage *f*³, and the vertically-arranged chamber *f*⁴ is situated eccentrically in the ice-receiver *f* and is in communication by the radial passage *f*³ with the water-chamber *g*, and the 75 ice-chamber *h* within the ice-receiver *f* is provided with a drip-tube *h*², which extends downwardly through the bottom of the tank *a* into the drip-chamber *c* and upwardly into 80 the ice-receiving chamber *h* a predetermined distance, and said drip-tube *h*² is preferably provided with one or more small perforations or holes *h*³ in the side or sides thereof.

In the form of construction shown the annular walls *a*² of the tank *a* are enlarged at the top to form an annular shoulder *a*⁶, on which is set a frame consisting of an annular band *i*, arranged eccentrically in the top of the tank *a* and formed by bending a bar of metal into 90 circular form and bringing the sides thereof together at *i*² and then extending said sides laterally and forming an arm, as shown at *i*³, the ends of which are connected by a segmental member *i*⁴, which rests on the annular shoulder *a*⁶, and the ring or band *i* opposite the member *i*⁴ rests on the annular shoulder *a*⁶, and the frame consisting of the parts *i*, *i*³, and *i*⁴ may be secured in position in any desired manner. The tank *a* is also provided 95 with a cover *j*, having a circular opening *j*², which corresponds with and registers with the ring or band *i*, and the cover *j* is composed of two parts, one of which is smaller than the other, as shown at *j*³, and is hinged 100 thereto, as shown at *j*⁴, and the smaller and hinged part *j*³ of the cover *j* is provided with a knob or handle *j*⁵, and said cover rests on the frame of which the ring or band *i* forms a part and also rests on the top of the tank *a* 105 and may be secured in place in any desired manner.

In practice the ice-chamber h of the ice-receiver f is filled or partially filled with ice, and this may be done through the opening j^2 in the cover j , and the hinged part j^3 of said cover may be raised for this purpose, and a bottle or other water receiver or holder k is placed on the top of the tank a in an inverted position, as shown in Fig. 1, and the neck k^2 thereof extends downwardly into the supplemental water-chamber f^1 . The bottle or other water-holder is preferably provided with a stopper k^3 , having a small port or passage through which the water gradually and slowly flows into the supplemental water-chamber f^4 , and as the water rises in said chamber it also flows into a recess in the main water-chamber g , and when the water reaches the neck of the bottle or the stopper k^3 therein the flow of water from the bottle will be cut off, as will be readily understood. The water may be drawn at any time from the tank a or the chamber g therein by means of the faucet e , and the water from the melting ice in the ice-chamber h will flow through the drip-tube h^2 into the drip-chamber c , from which it flows into bucket or other receptacle d^3 , and the object of the perforations or holes h^3 in the drip-tube h^2 is to permit the melting-ice water to flow through the drip-tube without rising to the top thereof or in case the top of said tube should become closed by ice lying thereon.

It will be seen that my improved water-cooler belongs to the class known as "fountain-cooler," the bottle or receptacle k forming a reservoir from which the water slowly flows in the manner described into the water chamber or chambers in the tank a , and this flow of water is automatically cut off whenever the water in said chambers reaches the lower end of the neck of the bottle, and said water can never flow into the water-chamber h , and the drip-tube h^2 is so arranged that the water from the melting ice can never flow into the water-chambers g , f^4 , or f^3 , all of which are in communication.

The drip-tube h^2 is removable and is preferably made tapered, as shown, so as to closely fit a corresponding opening m in the bottom of the tank a , the object of this construction being to provide means whereby the ice-chamber h may be entirely drained when necessary by the removal of said tube and whereby a portion of the melting water will be retained in said chamber when desired to aid in cooling the water in the chamber g .

My improved water-cooler is simple in construction and operation and comparatively inexpensive, and changes therein and modi-

fications thereof may be made without departing from the spirit of my invention or sacrificing its advantages.

Having fully described my invention, what I claim as new, and desire to secure by Letters Patent, is—

1. A water-cooler, comprising a tank adapted to receive the water to be cooled, an ice-chamber within and of smaller diameter than said tank, the vertical wall of said ice-chamber being inwardly curved to form a cylindrical recess and a contracted passage through which the recess communicates with the annular space surrounding the ice-chamber, a draw-off from said tank, a cover for said tank having an opening concentric with the cylindrical recess and adapted to support an inverted bottle with its neck entering said recess, a drip-chamber under the tank, and a removable drip-tube passing through the bottom of the ice-chamber, and communicating with the drip-chamber, substantially as shown and described.

2. A water-cooler, comprising a tank having a frame in the top thereof provided with a band or ring, a cover resting on said frame and provided with a circular opening over said band or ring and at one side thereof with a door, an ice-receiver within said tank and around which is a main water-chamber, the vertical walls of said ice-receiver being inwardly curved to form a vertically-arranged cylindrical recess and a contracted passage through which the receiver communicates with the water-chamber, and a removable drip-pipe passing through the bottom of the ice-receiver and communicating therewith, substantially as shown and described.

3. In a water-cooler, a tank adapted to receive the water to be cooled, an ice-chamber within and smaller than said tank, the vertical wall of the ice-chamber being inwardly curved to form a vertically-arranged recess and a passage through which the recess communicates with the annular space surrounding the ice-chamber, a draw-off for said tank, and a cover for said tank having an opening concentric with the vertically-arranged recess and adapted to support an inverted bottle with its neck entering said recess, substantially as shown and described.

In testimony that I claim the foregoing as my invention I have signed my name, in presence of the subscribing witnesses, this 19th day of February, 1904.

ERNEST OSCAR BUTT.
